George Bruce
Design for Printing Types

Patented Jan'y 6. 1857.

Des 863

Double Great-Primer Copperplate Script.

1-6-1857

Wishing to supply a Letter suitable for
Bill-heads, Notes, Drafts and Circulars, in which
but few lines are used, Mr. George Bruce has
executed this Double Great-Primer Copperplate
Script, which he now introduces to the Trade with
hopes for their approbation. Only the simplest of
wide letters of the alphabet are used and the flourishes
added to this specimen, in the few cases where they may
be required, are placed in such a manner as will soon be easily
got rid of. The specimen is given in the form of a
Sheet of paper, so that it may be easily
copied.

Dec. 863

George Bruce, of New York, N. Y.
Letters Patent No. 863. Dated Jan'y. 6. 1857.

The Schedule referred to in these Letters Patent and
making part of the same.

To all whom it may concern:

Be it known that I, George Bruce of the City and County of New York, in the State of New York, type-founder, have invented or produced a new set of printing-types, for letter-press printing, of a new and original design, which I describe as follows, referenced being had to the annexed printed impression thereof.

It is of the kind usually called script and of the size usually called Double Great Primer: but it differs from every other script-type in shape, size and proportion, and in the auxiliary flourishes which constitute a part of the set. I call this new type, Double Great Primer Loop-plate Script, and I claim the design of the said type as described and shown.

Witnesses:

D. W. Bruce,
John Sullivan
